UNITED STATES PATENT OFFICE.

JOSEPH M. TOWNE, OF EAST ORANGE, NEW JERSEY.

LOCK-LEVER CLIP FOR TEMPORARY BINDERS.

1,130,942.

Specification of Letters Patent.

Patented Mar. 9, 1915.

Application filed May 6, 1914. Serial No. 836,768.

To all whom it may concern:

Be it known that I, JOSEPH M. TOWNE, a citizen of the United States, residing at East Orange, Essex county, State of New Jersey, have invented certain new and useful Improvements in Lock-Lever Clips for Temporary Binders; and I do declare the following to be a full, clear, and exact description of the invention, such as will enable others skilled in the art to which it appertains to make and use the same.

My invention relates to certain improvements in lock lever clips for temporary binders, but has reference more particularly to temporary binders that are specially adapted to receive pamphlets, leaflets, catalogues, &c. The object of my improvement is not only to provide a binder which may be readily and independently attached to or disconnected from the usual posts or retaining members carried by a book back, but also to equip the binder with locking means so that accidental detaching of the binder clips is impossible. Furthermore, each separate pamphlet is independently connected to a binder post or other retaining member carried by the book back, so that any pamphlet may be inserted within or withdrawn from the binder without disturbing other pamphlets contained therein.

In the drawings Figure 1 is an elevation of my improvement showing the locking lever withdrawn—Fig. 2 a similar view showing the locking lever in its closed position with the retaining posts or members in section—Fig. 3 is a perspective view of a pamphlet in open condition, showing the slits made therethrough for the introduction of my improved device—Fig. 4 is an elevation of such pamphlet showing the manner in which the clips extend from the back of the same, and also showing in section a book back with retaining members in position to be engaged by said clips—Fig. 5 an elevation of one form of the lock lever, and Fig. 6 an elevation illustrating the form in which my improvement would be constructed when used in connection with pamphlets that are wire stitched.

Similar numerals of reference denote like parts in the several figures of the drawings.

1 is a sheet metal plate having formed integral therewith and extending from one edge a pair of clips 2 provided with open gates 3, which latter preferably extend in a

direction substantially parallel with the length of said plate.

4 is a locking lever which is pivoted at one end at 5 to the side of the plate 1 about midway of the length of the latter, and extending from the inner edge of the free end of said lever is a tongue-like member 6 which may be provided with an open gate 7.

8 represents a pamphlet, such as a catalogue, magazine or the like, and in applying my invention this pamphlet is opened, and slits 9 made from the inside through the back, these slits being spaced apart a distance equal to that which separates the clips 2. The plate 1 is then placed within the pamphlet with the clips 2 extending through the slits 9 and projecting from the back of the pamphlet as shown at Fig. 4, and these clips, which are in the nature of hooks, are then engaged around the binder posts or other retaining members 10 carried by the book back 11. The lock lever is then operated to cause the tongue 6 to be driven through one of the slits 9 alongside the plate 1 so that its open gate 7 will engage one of the posts 10, and in this connection it will be observed that, when in this engaged position, the gates 3 and 7 will extend in directions substantially at right angles, that is to say, the tongue 6 will really be athwart the gate 3 at a point immediately beyond the retaining member 10, so that the latter will be confined by said tongue within the gate or hook portion of the clip 2. The outer wall portions of the gates 3 yield resiliently to admit the retaining members 10, but this is not at all necessary since these clips 2 may be merely hook-like devices, since the tongues 6 when in locking position will effectually confine the retaining members 10.

Whether the clips 2 are mere hooks or are provided with open gates as shown. Likewise, the tongue 6 may be a mere hook-like member, or may be constructed as is shown at Fig. 5, since the friction between such tongue and the slot 9 in the pamphlet will prevent accidental displacement of the lever 4. Therefore, it is sufficient for the purposes of my invention, that the tongue 6 and its clip 2, when in locked position, should serve complementarily to inclose a retaining member 10, although I prefer the construction shown at Fig. 1.

The angular disposition of the gates 3 is immaterial although their arrangement in

a line substantially parallel to the length of the plate 1 is the simplest embodiment of my invention in this respect.

At Fig. 5 I have shown the lever 4 with

- 5 a plain tongue 12 extending therefrom, and, as I said before, this tongue will answer the purposes of my invention so long as it serves to confine the retaining member 10, and right here I will say that the latter may be
- 10 in any of the well known forms, either a post, ring, hook, prong, &c.

The form of my improvement illustrated at Fig. 1 would be used in connection with a saddle stitched pamphlet, magazine, &c., but

- 15 for a side wire stitched pamphlet or magazine I would employ the form shown at Fig. 6 where the width of the plate 1 is greater at its central portion, denoted by 13, which wider portion would be forced down against
- 20 the fold of the pamphlet or magazine while the narrow portions at the end, designated by the numeral 14, would rest against the wire stitching. In all other respects, the construction shown at Fig. 6 is precisely like
- 25 that shown at Fig. 1.

Having thus described my invention what I claim as new and desire to secure by Letters Patent is:—

1. In a device of the character described, 30 the combination of a binder plate having hook-like parts extending from one edge which receive the retaining members of a temporary binder, and a locking lever carried by said plate and having a portion extending from its inner edge and adapted in
- 35 closed position to coöperate with one of said projecting parts to complementarily inclose one of said retaining members.

2. In a device of the character described, 40 the combination of a binder plate having clips with open gates which receive the retaining members of a temporary binder, and a locking lever carried by said plate and adapted to be operated athwart the gate of
- 45 one of said clips and beyond a sheet retaining member.

3. In a device of the character described, 50 the combination of a binder plate having clips with open gates which receive the retaining members of a temporary binder, and a locking lever carried by said plate and having a tongue and adapted to be operated

to cause the latter to close the gate of one of the aforesaid clips immediately beyond the sheet retaining member contained 55 therein.

4. In a device of the character described, the combination of a binder plate having clips that extend from one of its edges and are provided with gates that open in a direction substantially parallel with the length 60 of said plate and that receive the retaining members of a temporary binder, and a locking lever pivoted to one side of said plate and having extending from its inner edge a 65 tongue which in the locked position of said lever closes one of said gates, whereby the sheet retaining members are confined in the latter.

5. In a device of the character described, 70 the combination of a sheet metal binder plate having clips that extend from one of its edges and are provided with gates whose side walls are resilient and which receive the retaining members of a temporary 75 binder, and a locking lever pivoted at one end to said plate about midway of the length of the latter and having extending from its inner edge near the other end a clip provided with a gate having resilient 80 side walls and adapted to receive one of said retaining members, the gates in the clips of said plate and lever opening in directions that are substantially at right angles. 85

6. In a device of the character described, the combination of a binder plate having clips with open gates adapted to be inserted through the back of a pamphlet from the inside thereof and engaged with retaining 90 members carried by a book back, and a locking lever pivoted to the side of said plate and having a tongue extending from the inner edge of its free end, said lever adapted to be swung to drive said tongue through 95 said pamphlet athwart the outer portion of one of said gates, thereby locking said retaining members within the latter.

In testimony whereof I affix my signature in presence of two witnesses.

JOSEPH M. TOWNE.
